UNITED STATES PATENT OFFICE

151,242

DESIGN FOR A BOAT

John E. Jones, Long Beach, Calif., assignor to
James C. Whittaker Co., Inc., Long Beach,
Calif., a corporation of California

Application February 7, 1947, Serial No. 136,772

Term of patent 7 years

(Cl. D71—1)

To all whom it may concern:

Be it known that I, John E. Jones, a citizen of the United States, residing at 4115 E. Second Street, Long Beach, in the county of Los Angeles and State of California, have invented a new, original, and ornamental Design for Boat, of which the following is a specification, reference being had to the accompanying drawing, forming a part thereof.

Figure 1 is a top plan view of a boat showing my new design.

Figure 2 is a side elevation of the same.

Figure 3 is a front view of the same.

I claim:

The ornamental design for a boat, as shown.

JOHN E. JONES.
